(57) CLAIM

The ornamental design for a to-go cup, substantially as shown and described.

DESCRIPTION

FIG. 1 is a front-top perspective view of a to-go cup. FIG. 2 is a front view of the to-go cup of FIG. 1. FIG. 3 is a left-side view of the to-go cup of FIG. 1. FIG. 4 is a right-side view of the to-go cup of FIG. 1. FIG. 5 is a top view of the to-go cup of FIG. 1; and, FIG. 6 is a bottom view of the to-go cup of FIG. 1. The dash-dash broken lines shown in the drawings depict portions of the to-go cup that form no part of the claimed design. The dash-dot broken lines shown in the drawings depict the boundary of the claim and form no part of the claimed design.
